UNITED STATES PATENT OFFICE.

LARS R. JORGENSEN, OF SOUTH BERKELEY, CALIFORNIA.

DAM CONSTRUCTION.

1,216,234.

Specification of Letters Patent. Patented Feb. 13, 1917.

Application filed December 27, 1915. Serial No. 68,679.

To all whom it may concern:

Be it known that I, LARS R. JORGENSEN, a citizen of the United States, residing at South Berkeley, in the county of Alameda and State of California, have invented new and useful Improvements in Dam Construction, of which the following is a specification.

This invention relates to improvements in the construction of dams, and especially dams of the arch type, of such large proportion that it is not economical to reinforce the body with steel to keep it from cracking.

It consists in providing the dam with contraction, or slip joints at spaced intervals, and in a means and devices to inject a water-tight grout into said joints, after the dam has been subjected to a maximum load or has acquired a permanent set, and shrinkage is completed.

It also comprises details of construction which will be more fully described by reference to the accompanying drawings, in which—

25 Figure 1 is a vertical section of a dam, showing the pipes for grouting the joints.

Fig. 2 is a partial vertical section, showing the grout pipe.

Fig. 3 is a section on line 3—3 of Fig. 2.

30 Fig. 4 is a section showing the disposition of the pipes when the wall is thin.

Fig. 5 is a detail of the pipe.

Fig. 6 is a vertical section of same.

Fig. 7 is a section of the end of the grout 35 pressure pipes.

Fig. 8 is a plan section on line 8—8 of Fig. 7.

Whenever the cross section of an arch dam becomes of such large proportions that it is not economical to reinforce it with steel to keep it from cracking, contraction or slip joints are usually provided at spaced intervals along the arch, as at 2, Fig. 3. When the dam has been loaded at least once, the 45 body has taken its permanent set, besides all the shrinkage, due to the setting of the concrete, has occurred. With the reservoir empty during cold weather the contraction joints will then be open a maximum under 50 these conditions. In order to make the arch water-tight, grout should be injected into the contraction joints to close them under this condition of maximum opening up.

A simple way of doing this would be to 55 insert pipes into the contraction joints when the dam is built. These pipes 3, shown in

Figs. 4, 5 and 6, are to have their lower ends flattened somewhat, as at 4, and are to be provided with slots 5 at spaced intervals. The pipes are to be inserted in the 60 dam body in such a way that the slots are in line with the contraction joint.

Inside of such a stationary pipe a smaller diameter pipe 6 is to be slipped, provided at the lower end with a packing ring 7^a to 65 close up the space between the inside of the stationary pipe and the outside of the movable pipe. At its upper end this movable pipe is to be connected to a grout pump (not shown). The grouting proceeds from below, 70 up through the lower end and through successive slots in the outer pipe; the inside pipe being raised as fast as necessary. The 75 slots are to be covered with cheese-cloth, or paper, or similar material, to prevent the closing of the same, when concrete is being poured around them as construction progresses, so as to allow a free passage for the grout after the inside pressure has burst the cheese-cloth covering.

80

Where the dam section is large a disposition of the grout pipes, such as shown in Figs. 1, 2 and 3, will be the most practical. Here one or more vertical, or nearly vertical, pipes 3^a feed a system of horizontal, or 85 nearly horizontal, pipes 7 at different elevations. The horizontal pipes are provided with slots 5^a for the grout to escape in an up-and-down direction into the contraction joints in a like manner as described above, 90 so as to fill up these joints. The contraction joints may be shaped such that one or more vertical pipes with a system of horizontal pipes each may be necessary for the successful grouting of a complete joint, as shown 95 in Fig. 3.

For small dam sections it may be sufficient to have inserted a few pipes straddling the contraction joints, the lower ends of which are located at different elevations and having these points of exit distributed as regularly as practical over the whole section.

Having thus described my invention, what I claim and desire to secure by Letters Patent is—

105

1. A dam body having grout pipes inserted in the contraction joints and distributed over the whole section, the ends of these pipes preferably flattened to form a slot and the sides of the pipes provided with 110 short longitudinal slots at spaced intervals, these permanent pipes having movable pipes

of smaller diameter inserted, the space between the two pipes being made tight at the lower end of the movable pipe by means of a packing, and said lower end of the movable pipe serving as a discharge for the grout into the large pipe and the upper end being connected to a grout pump.

2. A dam body having one or more vertical or nearly vertical unperforated pipes inserted in line with the contraction joint and a system of approximately horizontal pipes branching off from these vertical pipes, said branch pipes being provided with short slots at intervals in line with the contraction joints, and their ends being preferably flattened to also form a slot in line with the joint.

3. A dam body having one or more approximately vertical pipes inserted in line with the contraction joint and a system of horizontal, or nearly horizontal, pipes

branching off from these vertical pipes, said branch pipes being provided with short slots at intervals in line with the contraction joints, and their ends being flattened to also 25 form a slot in line with the joint, said vertical pipes having inserted movable pipes of smaller diameter, the space between the two pipes being made tight at the lower end of the movable pipe by means of a packing, 30 and the lower end of the movable pipe serving as a discharge for the grout into the larger pipe, the upper end of the movable pipe being connected to a grout pump.

In testimony whereof I have hereunto set 35 my hand in the presence of two subscribing witnesses.

LARS R. JORGENSEN.
